(57) **CLAIM**

The ornamental design for a “infant carrier cover,” as shown and described.

DESCRIPTION

FIG. 1 is a perspective view of an infant carrier cover, showing my new design exploded from an infant carrier. The infant carrier shown in broken lines forms no part of the claimed design.

FIG. 2 is a perspective view thereof shown on an infant carrier. The infant carrier shown in broken lines forms no part of the claimed design.

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

Dashed lines across the rear inner and outer patches in FIGS. 4, 7, and 8 represent stitching, and form part of the claimed design.
